UNITED STATES PATENT OFFICE

93,113

DESIGN FOR AN AMUSEMENT GAME CABINET

Claude R. Kirk, Oak Park, Ill., assignor to John F. Meyer, Chicago, Ill.

Application June 14, 1934, Serial No. 52,177

Term of patent 3½ years

To all whom it may concern:

Be it known that I, CLAUDE R. KIRK, a citizen of the United States, residing at Oak Park, in the county of Cook, and State of Illinois, have invented a new, original, and ornamental Design for an Amusement Game Cabinet, of which the following is a specification, reference being had to the accompanying drawing forming part thereof, and in which:

The single figure is a perspective view showing the new design.

I claim:

The ornamental design for an amusement game
cabinet as shown.

CLAUDE R. KIRK.
